(57) **CLAIM**

We claim the ornamental design for a screw-top container, as shown and described.

DESCRIPTION

FIG. 1 is a perspective view of a screw-top container, embodying our new design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1; and,

FIG. 6 is a top view of the claimed design of FIG. 1.

The broken lines shown are included for the purpose of illustrating the unclaimed portions of the screw-top container and form no part of the claim.

1 Claim, 6 Drawing Sheets
